PULL ROD CARRIER

Allen M. Rossman, Wilmette, Ill.

Application October 30, 1942, Serial No. 463,959

17 Claims. (Cl. 74—522.5)

This invention relates to pull rod carriers, and more particularly to carriers of the type shown in my pending application, Serial No. 272,865.

In certain oil well districts horizontally reciprocating pull rods are used for transmitting power from a central engine or source of power to each of a plurality of pumps, some of which may be thousands of feet from the source of power. Each pull rod is supported by carriers every twenty-five or so feet in order to prevent excessive sagging of the pull rod, or to prevent dragging on the ground. The pull rod carrier of the present invention comprises a series of pivotally interconnected links supported on a stationary support set into a foundation or foundations in the ground and supporting the carrier and guiding it in a straight horizontal line as the pull rod reciprocates. The reciprocating movement of the pull rod actuates the supporting linkage and although the linkage reciprocates with the rod the parts of the linkage that directly support the rod move in substantially a straight line.

The supporting carrier of the present invention comprises two side links or arms pivotally connected at their upper and lower ends to upper and lower bars or links of unequal size to form a quadrilateral. The load placed on the carrier by the rod is supported by the side arms or links. It is one of the objects of the present invention to provide a construction of the side arms or links such as will not be subjected to bending or torsion stress so that all of the stress therein will be either tensile or compressive stress. This is accomplished, in the preferred construction, by making each link in the form of a pair of balanced members which are spaced equally on opposite sides of the path of motion of the pull rod and thus eliminate all bending stresses in those members. This makes for stability of operation and even wear on the bearings.

It is a further object of the present invention to provide a carrier wherein the bearing parts are all wood and an integral part of one or the other of the two linkage members that are journaled together at the bearing. By this arrangement the bearings cannot rock with respect to the carrier. This further reduces the possibility of wearing enlarged holes at the bearings. Furthermore, by this arrangement the bearing holes can be drilled in the wooden members to the correct dimensions, thereby producing a structure which is true initially and permanently. Steel members that are bent to shape to support the bearings are not always bent true and may not always retain the true shape.

It is a still further object of the present invention to provide a pull rod carrier wherein certain parts that are made of steel may be made in a simple and economical manner and be sturdy of construction.

- 5   The attainment of the above and further objects of the present invention will be apparent from the following specification taken in conjunction with the accompanying drawings forming a part thereof.
- 10   In the drawings:
Figure 1 is a top view of a pull rod carrier embodying the present invention;
Figure 2 is a side view of the carrier of Figure 1;
Figure 3 is a sectional view taken along the line 3—3 of Figure 2 and looking in the direction of the arrows;
Figure 4 is an end view of the carrier of Figure 2;
Figure 5 is an enlarged sectional view taken along the line 5—5 of Figure 1 and looking in the direction of the arrows;
Figure 5a is a perspective view of a carrier supporting block;
15   20   Figure 6 is a top view of a modified form of cross member;
Figure 7 is a fragmentary sectional view taken along the line 7—7 of Figure 6;
Figure 8 is an end view of an alternate pivotal connection at the bottom of the side arms of the carrier of Figure 2;
Figure 9 is a front view showing a modified form of carrier corresponding to Figure 2;
Figure 10 is an enlarged fragmentary sectional view of a portion of Figure 9;
25   30   Figure 11 is a top view of still another carrier embodying the present invention;
Figure 12 is a side view of the carrier of Figure 11;
Figure 13 is a sectional view taken along the line 13—13 of Figure 12; and
Figure 14 is a sectional view taken along the line 14—14 of Figure 12.
- 35   40   45   In the various figures of drawings like reference numerals designate like parts throughout. Reference may now be had more particularly to the embodiment of the invention illustrated in Figures 1, 2, 3 and 4. A portion of a horizontally reciprocating pull rod is illustrated at 1. The pull rod may be several thousand feet in length and is reciprocated to transmit power from a source of power to a pump of an oil well, and is supported above the ground every twenty-five feet or so by a carrier such as the carrier 2. The carrier is mounted on a single support com-

prising a vertical pipe 3 of steel or the like, which is firmly set into the ground or in a foundation in the ground. The foundation pipe 3 is open at the top and receives the stem 4 of a T-shaped wooden support 5 the web of which is indicated at 6. The stem 4 of the support may be an integral part of the web 6, and is circular in cross section and makes snug driven fit in the pipe 3. The web 6 of the support 5 has a horizontal bore 7 formed therethrough which constitutes a support for a bearing pin or tube 8 that is the pivot upon which the carrier is supported and about which it swings.

The carrier 2 includes a cross member 10 in the form of a wooden beam having four parallel holes formed transversely therein. Two of the holes are provided for receiving bolts 11 and 12 and are located midway between the top and bottom surface thereof as seen in Figure 2. The other two holes, of which more will be stated as this description proceeds, are holes for receiving pivot tubes 14 and 15. These holes are not located on the longitudinal center of the member 10 but rather a short distance above the longitudinal center so that there is appreciably more wood of the beam 10 below the holes for the pivot tubes 14 and 15 than above them, for a reason which will be apparent as this description proceeds. The bolts 11 and 12 rigidly secure two pairs of wooden struts 17-17 and 18-18 to the cross member 10. The pair of struts 17 diverge from the cross member 10 and the pair of struts 18 also diverge from the cross member 10, as may be seen in Figure 1. The two pairs of struts converge towards one another, as may be seen in Figures 1 and 2, and extend on opposite sides 9-9 of the support 5. The two pairs of struts are secured together by the pivot tube 8. It is thus apparent that the cross member 10 and the four struts 17-17 and 18-18 constitute one rigid structure pivoted about the center of the tube 8. The struts 17-17 and 18-18 are chamfered off at their top ends as may be seen more fully in Figure 5, to facilitate bolting of the ends of the struts to the cross member 10.

Identical links 20-21 are pivoted at their upper ends to the bar 10 by the pivot tubes 14-15. Each of the links 20-21 comprises a pair of wooden side bars 22-22 that are spaced a fixed distance on opposite sides of the cross bar 10 by identical wood spacer blocks 23-23 that are bored to receive the pivot tubes 14 or 15, as the case may be. At their lower ends the links 20-21 are pivoted to a bottom link 25 by pivot tubes 26, the side bars of the links 20 being spaced from the link 25 by wooden spacer blocks 27-27, shown more particularly in Figure 4. The spacer blocks 27-27 have holes formed therein through which the associated pivot tube 26 extends. In addition, each of the blocks 27-27 overlies a portion of the top of the link 25, as may be seen from Figure 4, the space between the adjacent blocks 27-27 at the top of the link 25 being just sufficient to allow the pull rod 1 to fit between the blocks and rest on the link or bar 25. The links 20-21 thus support the link 25 upon which the rod 1 rests, and the rod is prevented from shifting sidewise on the link 25 by the spacer blocks 27-27 while permitting freedom of sliding movement of the rod lengthwise of the link 25.

The pivot tubes 8, 14, 15 and 26 are held in place against sliding out of the bearings in any desired manner as, for instance, by small wires or pins 29 each of which is passed through aligned

holes in the end of the tube and then bent to hold it in place.

All wood parts are rough cut and thoroughly dried and then soaked in crude oil before being put into service. The bearings are lubricated with a heavy grease before assembling the carriers. Thereafter no subsequent lubrication is required.

It is to be noted that the link 25 extends an appreciable distance beyond the links 20-21 on opposite sides of the carrier, and supports the rod 1 at the portions 32-32 beyond the linkage. The proportions of the links are such that with the pivot axis 8 stationary, then so long as the pivots 26-26 are maintained in horizontal alignment their direction of movement as the linkage is actuated will be in substantially a straight horizontal line. The weight of the pull rod itself maintains the link 25 horizontal by reason of the extensions 32-32. Any tendency for the left hand pivot 26 to drop below that of the right hand pivot 26 would result in tilting of the link 25 and raising of the right hand end extension 32. The weight of the rod itself prevents such rise and thereby prevents either pivot 26 from dropping below the level of the other pivot 26.

In the carrier illustrated in Figure 2 the overall complete length of the link 25 is seven feet. If the length of unsupported portions of the pull rod 1 between adjacent carriers is to be twenty-five feet, by way of example, then the center to center distance between foundation posts 3 for adjacent carriers would be made thirty-two feet.

As the pull rod moves, for instance, to the left from the position illustrated in full lines in Figure 2, the carrier 2 moves from the full line position of that figure to the dotted line position. When it reaches the dotted line position the side bars of the link 21 abut against the web 6 of the T-support 5 or against the lower ends of the struts 17-17 and thus hold the carrier against further swinging about the pivot 8. Continued movement of the rod 1 to the left results merely in sliding of the rod 1 along the link 25 until the rod reaches the end of its stroke. Thereafter, on reverse horizontal movement of the rod 1, the linkage 2 tilts from the dotted line position of Figure 2 back to the full line position and then continues tilting to another position on the opposite side of the center 8 corresponding to the dotted line position here illustrated. The stroke of the straight line motion mechanism is twice the distance of travel of the pivot 26 of the link 21 from the full line position of Figure 2 to the dotted line position of Figure 2. The linkage is designed so that its full stroke is slightly in excess of the amplitude of the stroke of the reciprocating pull rod 1. Thus during the initial movement of the pull rod after assembly of the carrier the pull rod adjusts itself on the carrier by sliding along the carrier after the carrier has reached its limiting stop position. Once this adjustment has been made continued reciprocation of the pull rod results in a corresponding to and fro movement of the link 25 with no sliding movement between the pull rod and the link 25 of the carrier. The pull rod is thus supported and guided in its reciprocating movement without any sliding of the pull rod.

During the major portion of the cycle of travel of the pull rod the weight thereof places the links 20 and 21 in tension so that the tubes 14-15 are exerting their pressure on the bottom surfaces of the bearing holes in the cross member 10. Those surfaces of the bearings therefore re-

ceive the most wear, and for that reason the holes for the bearings 14-15 in the member 10 are placed slightly above the center of the member to provide more material below the bearings where wear takes place. On the other hand, at the bearings 26-26 of the link 25 the link 25 exerts its pressure on the bearing tubes at the top surfaces of the bearing holes during the major part of the cycle of travel of the pull rod. The major wear therefore takes place at the top surfaces of the bearing holes in the link 25, and the bearing holes are therefore located below the center of that link to provide more material above the bearing holes, where the wear takes place.

Figure 6 shows an alternate construction of the cross member 10. In this construction the cross member is indicated at 10'. At its opposite ends the bar or cross member 10' has enlarged heads 38-38 through which holes 39-39 are formed for receiving the pivot tubes 14 and 15, respectively. The cross member 10' may be made from a single wooden member cut out to the shape illustrated in Figure 6. When this is done the sides of the cross member 10' may be cut at an angle, as illustrated in Figure 7, and the upper ends of the struts 17-18 need not be chamfered. The enlarged heads 39 provide the necessary spacing for the side bars 22-22 thus eliminating the need for the upper spacers 23-23 of Figures 1 and 4. Also, spacers 27-27 at the lower ends of the bars 22-22 may be replaced by a single rectangular wooden spacer block 27', as illustrated in Figure 8. The spacer block 27' extends between the bars 22-22 and is pivoted on the pivot tube 26. The link 25 is then supported by the two spacer blocks 27' one of which is located at the bottom of the side bars of the link 20 and the other of which is located at the bottom of the side bars of the link 21. The link 25 is secured to each spacer bar 27' by two sets of side by side bolts 40-40 each of which extends through the spacer block 27' and through the link 25 and a short distance above the link 25 so that the spaced shanks of the bolts, indicated at 41-41 in Figure 8, hold the rod 1 against sidewise movement off of the link 25. The bolts 40 are kept in place by nuts threaded thereon and resting in countersunk holes at the top of the link 25.

In the embodiments of the invention illustrated in Figure 2 each carrier is supported by a single support. Some terrain encountered is such that it is more economical to use two supports than to attempt to obtain the requisite rigidity from a single support. When this is the case the carrier of Figure 2 can be mounted in a somewhat different manner, as illustrated in Figure 9. In this figure two supports 3-3, of the same construction as previously described in Figure 2, are mounted in the ground in alignment, a proper distance apart, and each has at the top thereof a T-shaped support 5. In this instance the link 25 of Figure 2 is omitted, and the side bars of the links 20-21 are pivoted to the stationary supports 5 by the pivot tubes 8a and 8b, each of which extends through the bearing hole 7 in one of the supports 5. The links 20 and 21 are connected together at their upper ends by the cross member 10 which has the struts 17 and 18 secured thereto in a manner previously described, and carries a support 42 in the form of a block located between the two struts 17-17 and the two struts 18-18 and pivoted between the struts by a tube 43. In this construction the distance

between the pivots 8a-8b is made proportionately longer than between the pivots 26-26 of Figure 2 in order to allow the foreshortening of the struts 17-18 to bring the pivot point 42 above the pivots 8a-8b while maintaining the straight line motion characteristics of the carrier. The distances between the pivots 8a and 14 is the same as between the pivots 8b and 15, and the distances between the pivots 14-15 and 43 are such that the pivot 43 moves in substantially a straight line as the carrier is rocked about the stationary pivots 8a-8b. The pivot axis 43 is equidistant from the pivot axes 14-15. The pull rod 1 is supported on the block 42 in any desired manner to permit sliding of the pull rod on the block and to hold the pull rod against shifting off of the block sidewise. This may be accomplished by forming a V-shaped pull rod receiving groove extending lengthwise in the top of the block 42 in the manner illustrated in my pending application, Serial No. 272,865. The block 42 at its opposite extremes of motion abuts against the web of the T-shaped support 5 on one or the other of the pipes 3 to limit the longitudinal movement of the support 42 to an amount slightly in excess of the amplitude of the stroke of the pull rod 1. To brace the foundation the posts 3-3 are secured together by a wooden strut 46 that bears against the supports 5-5 and is secured thereto by bolts 47, as may be seen from Figure 10.

The mode of operation of the carrier of Figure 9 is substantially the same as that of the carrier of Figure 2 except that the rod 1 is supported only by the block 42.

Reference may now be had more particularly to Figures 11, 12, 13 and 14 which show another embodiment of the present invention. In this construction the foundation 3 and the support 5 are the same as illustrated in Figure 3. The cross member 10a, which corresponds to the cross member 10 of Figure 2, is pivoted on the support 5 by means somewhat different from the struts 17 and 18 of Figure 2. The mounting for the cross member 10a consists of a steel rod 49 bent to have a horizontal portion 50 which is adapted to be extended through the bore 7 of the support 5 and journaled therein. The rod is bent at 51 to form a portion 52 that extends upwardly and towards the center of the support 5, as indicated in Figure 14, and is then bent to form three legs of a triangle, indicated at 54, 55 and 56. The part 56 is welded to the part 54 at 57 to increase the rigidity of this structure. From the leg 56 of the triangle the rod continues, as indicated at 57, to and overlapping the horizontal part 50 adjacent the curve 51 and is welded thereto, as indicated at 58, to strengthen the member and avoid bending of the part 52 with respect to the part 50 at the curve 51 when the carrier is in use. The part 55 of the bent rod support is bolted to the cross member 10a in any desired manner as, for instance, by two U-bolts 60 that embrace the part 55 and extend through holes in the cross member 10a and are held in place by nuts 61. Due to the welds at 57 and 58 it is apparent that the cross member 10a is supported rigidly and firmly by the bent rod, and immovable with respect to the part 50 thereof, which is journaled in the support 5 by the cross member 50. A pair of pins 63-64 are passed through aligned holes in the bearing part 50 to hold that part against sliding lengthwise in the bearing. A pair of identical Z-shaped links 20' and 21', which correspond respectively to the links 20 and 21

of the carrier of Figure 2, are provided. Each of these links comprises a steel rod bent into Z-shape, as illustrated in Figures 11 and 13, to provide a pair of horizontal bearing arms 65—66. The upper arms of the two links 20'—21' are extended through holes in the cross member 10a and journalled therein to swing about pivot axes 14'—15', respectively, whereas the lower arms of the two links are extended through holes in a cross member 25' and journalled therein about axes indicated at 67—68. The distance between the centers 14'—67 is the same as the distance between the centers 15'—68. The center of the part 50 about which the cross member 10a swings is equidistant from the pivot axes 14' and 15'.

The arms 65—66 of the links 20'—21' may be retained against sliding out of their bearings in the cross member 10a and in the cross member 25' in any desired manner as, for instance, by pins 70—70 that are passed through holes in the arms 65—66 on opposite sides of the link 10a and 25'.

The pull rod 1 rests on the link 25' and is freely slidable thereon longitudinally of the link 25', and is held against movement sidewise of the link by two pairs of side by side bolts 41—41 passing through the link on opposite sides of the pull rod, in the same manner as in Figure 8, and embracing the pull rod.

The centers of the holes in the cross member 10a for the centers 14'—15' are located closer to the top of the cross member 10a than to the bottom thereof, whereas in the link 25' the centers 67—68 are located closer to the bottom of the link than to the top thereof for the same reasons as in the structure of Figure 1. The operation of the carrier of Figure 12 is substantially the same as that of Figure 1. The limit of motion in one direction or the other of the carrier is reached when one or the other of the links 20'—21' abuts against the part 51 of the rod 49 in either direction of travel of the carrier from the center position. The stroke of the carrier is slightly greater than the stroke of the pull rod.

It is to be noted that the pull rod 1 may be bodily lifted off of the carrier of Figure 11 and moved sidewise and lowered to the ground.

In compliance with the requirements of the patent statutes I have here shown and described a few preferred embodiments of my invention. It is, however, to be understood that the invention is not limited to the precise constructions here shown, the same being merely illustrative of the principles of the invention. What I consider new and desire to secure by Letters Patent is:

1. Apparatus of the class described including a T-shaped support, means for holding the stem of the T in position, and a pull rod carrier pivoted on the web of the T-shaped support about an axis extending lengthwise through the web.

2. Apparatus of the class described including a T-shaped support, means for holding the stem of the T in position, the web of the T having a bore extending lengthwise therethrough, and a pull rod carrier pivoted on the support by means including a pivot member extending through said bore.

3. Apparatus of the class described comprising a pipe fixed in a vertical position, a T-shaped support the stem of which extends into and fits snugly within the top of the pipe and the web of which projects horizontally from the pipe, and a pull rod carrier pivoted on the web of the support

about an axis extending horizontally lengthwise of the web of said support.

4. A straight line motion mechanism comprising a cross bar, side arms pivoted to the ends of the cross bar by means extending through the ends of the cross bar, converging members rigidly secured to the cross bar and secured together, a pivot axis for the converging members located equal distances from the pivots of the side arms with the cross bar, a link, additional pivot axes connecting the respective side arms to said link, the distance between said additional pivots being greater than the distance between the pivots of the side arms with the cross member.

5. A straight line motion mechanism comprising upper and lower wooden bars, side arms pivoted to the upper and lower bars to form a quadrilateral with the distance between pivots on one of the bars greater than the distance between the pivots on the other bar, the pivot axes extending through the bars and the bars constituting the bearings, and a stationary support, and means for pivoting the shorter of the two bars to the support about a single axis located equidistant from the pivot axes of the arms with said shorter bar.

6. A straight line motion mechanism including a first pair of spaced side bars, a second pair of spaced side bars, a cross member between said pairs of side bars and pivotally connected at its opposite ends to one end of each pair of side bars, spacers between said cross member and the side bars of each pair, pivot means including a pair of spaced pivots at the opposite ends of the side bars a fixed distance apart greater than the distance between the pivots of the cross member, another pivot means a fixed distance from the cross member and located equidistant from the axes between the cross member and the side bars, one of the two pivot means comprising a support for the mechanism and the other comprising a support for a reciprocating object to be guided in a straight line by the mechanism.

7. Apparatus for supporting a longitudinally reciprocating pull rod intermediate the ends thereof, said apparatus comprising straight line motion mechanism including a first pair of spaced side bars, a second pair of spaced side bars, a cross member pivotally connected at its opposite ends to one end of each pair of side bars, pivot means including a pair of spaced pivots at the opposite ends of the side bars a fixed distance apart greater than the distance between the pivots of the cross member, another pivot means a fixed distance from the cross member and located equidistant from the axes between the cross member and the side bars, the pull rod extending centrally between the bars of the first pair of side bars and between the bars of the second pair of side bars, one of the two pivot means comprising a support for the mechanism and the other comprising a support for the pull rod to be guided in a straight line by the mechanism.

8. A straight line motion mechanism including a pair of links, a cross member pivotally connecting the links at one end, a pair of spaced pivot means for the opposite ends of the links, means for maintaining the spaced pivot means a fixed distance apart greater than the distance between the pivots of the cross member, stationary pivotal support means a fixed distance from the cross member and located equidistant from the axes between the cross member and the links, the pair of spaced pivot means comprising a support for a reciprocating object to be guided in a straight line by the mechanism.

75 9. A pull rod carrier for a reciprocating sub-

stantially horizontal pull rod of such length as to require support between its ends to prevent excessive sagging of the rod, said carrier comprising a pair of equal links having parallel pivot axes at an end of each thereof, a third link pivoted to said pair of links at said axes, a cross member pivotally joining the opposite ends of the links, the distance between the cross member pivot axes being substantially less than the distance between the first mentioned pivot axes, means for supporting the cross member about a single fixed pivot axis equidistant from the pivots between the cross member and the links, said third link extending beyond its pivots with the pair of links for engagement with a pull rod beyond said last mentioned pivots to prevent tilting of the third link.

10. A pull rod carrier for a reciprocating substantially horizontal pull rod of such length as to require support between its ends to prevent excessive sagging of the rod, said carrier being a straight line motion mechanism comprising a pair of equal links and means for holding their ends a fixed distance apart, said means including parallel pivot axes at the ends of the links and a cross member pivotally joining the links; and means for pivoting the cross member about a stationary pivot axis at a fixed distance from the cross member and equidistant from the pivots between the cross member and the links.

11. A pull rod carrier for a reciprocating substantially horizontal pull rod of such length as to require support between its ends to prevent excessive sagging of the rod, said carrier comprising a pair of equal links and means for holding their ends a fixed distance apart, said means including parallel pivot axes at the ends of the links and a cross member pivotally joining the links; and another pivot axis at a fixed distance from the cross member and equidistant from the pivots between the cross member and the links, said other pivot axis and the first mentioned pivot axes being relatively movable with respect to one another in a straight line under the guidance of the cross member and the said links, each of said links comprising two side by side members located on opposite sides of the load supported by the carrier and dividing the stress of the load on the link between them, said cross member comprising a beam each end of which is enlarged to form a head which is embraced by the side by side members of a link.

12. A pull rod carrier comprising a pair of equal links, means including a pair of parallel pivot axes connecting the links at one end and maintaining the links a fixed distance apart at the connection, a cross member pivotally joining the links at their opposite ends, a rigid metal member rigidly secured to and extending lengthwise of the cross member, the ends of the metal member projecting from the cross member and converging towards one another and forming a frame, one end of the metal member extending at right angles to the cross member with the center of said one end located equidistant from the pivot axes of the links with the cross member and constituting another pivot axis, said other pivot axis and the first mentioned pivot axes being relatively movable with respect to one another in a straight line under the guidance of the cross member and the said links.

13. A pull rod carrier for a reciprocating substantially horizontal pull rod of such length as to require support between its ends to prevent excessive sagging of the rod, said carrier comprising

ing a pair of sets of equal links and means for holding their ends a fixed distance apart, said means including parallel pivot axes and a cross member pivotally joining the sets of links and embraced by the links of each set; converging sets of supporting means rigidly secured to and embracing the cross member adjacent to but spaced from the respective pivots between the cross member and the links, and another pivot axis at the supporting means at a fixed distance from the cross member and equidistant from the pivots between the cross member and the links, said other pivot axis and the first mentioned pivot axes being relatively movable with respect to one another in a straight line under the guidance of the cross member and the said links.

14. In a straight line motion mechanism a cross bar, a pair of struts one end of each of which is secured to the cross bar at one end thereof and diverging from one another, a second pair of struts one end of each of which is secured to the cross bar at the opposite end of the cross bar and also diverging from one another, means securing the opposite ends of the two pairs of struts together, said means including means for maintaining said opposite ends of the struts of each pair spaced apart an amount in excess of the thickness of the cross bar.

15. A straight line motion mechanism comprising four links pivoted together to constitute a quadrilateral, two opposite links being of equal effective lengths and the other two being of unequal effective lengths, means for pivotally supporting the shorter of the unequal links to swing about a single fixed pivot axis, the longer of the two unequal links extending beyond each of its two pivotal connections in the quadrilateral for engaging, beyond those two pivotal connections, an object to be guided by the mechanism.

16. In combination with a substantially horizontal reciprocating pull rod, a carrier supporting the rod intermediate its ends and comprising a straight line motion mechanism pivoted about a single stationary axis and including a link and means supporting the link about two spaced parallel and movable axes which are constrained by the mechanism to a straight line horizontal motion only while the two movable axes are held at the same horizontal levels, said link having means engaging said pull rod at locations spaced apart a distance greater than the distance between said movable axes whereby the rod prevents vertical tilting of the link to move either movable axis below the other movable axis.

17. In combination with a substantially horizontal longitudinally reciprocable pull rod, a carrier supporting the rod and comprising means for supporting a pair of spaced movable pivots a fixed distance apart and constraining the movement of the pivots to an arcuate path having one fixed center, a pair of equal links pivotally supported by and swingable about said movable pivots, a third link pivotally connecting and supported by the said pair of links, and pull rod supporting means connected to the third link, said third link extending beyond the pivots between it and the first two links and engaging the pull rod on opposite sides of the carrier a distance apart greater than the distance between the pivotal connections of the third link with the two first mentioned links, whereby the horizontal pull rod maintains said third link against tilting out of the horizontal position.
